UNITED STATES PATENT OFFICE.

CHARLES JACOB GUSTAFSON, OF CHATTANOOGA, TENNESSEE.

SELF-OILING JOURNAL-BOX.

No. 807,874.

Specification of Letters Patent.

Patented Dec. 12, 1905.

Application filed January 30, 1904. Serial No. 191,374.

To all whom it may concern:

Be it known that I, CHARLES JACOB GUSTAFSON, a citizen of the United States, residing at Chattanooga, in the county of Hamilton and 5 State of Tennessee, have invented a new and useful Self-Oiling Journal-Box, of which the following is a specification.

My invention relates to journal-boxes, such as are employed to receive and support the 10 ends of the axle on railway-cars, and has for its object to produce a simple inexpensive device of this character designed to carry a supply of lubricant and feed the latter regularly and evenly to the journal.

15 To these ends the invention comprises the novel features of construction and combination of parts more fully hereinafter described.

In the accompanying drawings, Figure 1 is 20 a side sectional elevation showing my improved journal-box applied for use. Fig. 2 is an end elevation of the same. Fig. 3 is a section on the line 3 3 of Fig. 1.

Referring to the drawings, 1 designates a car-axle having mounted thereon a wheel 2, 25 beyond the outer side face of which the axle is extended to form a journal 3, having bearing for rotation in a journal-box 4, attached to the longitudinal sill 5 of a car. These parts, with the exception of the journal-box, 30 may all be of the usual or any preferred construction and assembled in the ordinary or any desired manner.

The journal-box 4, constituting the subject-matter of this invention, and which receives and supports the journal 3, is preferably formed of a single casting and is provided with a central enlargement 4', defining oppositely-disposed laterally-projecting seating-flanges 5', adapted to receive the longitudinal sill, said journal-box being secured to the sill 5 by means of bolts 6', which pass through perforations in the ears or lugs and engage alined openings in the longitudinal sill, as shown. The journal-box 4 is provided 45 with a bearing-face 6, between which and the adjacent face of the journal there is disposed, as usual, a journal-brass 7, while beneath the journal and at the outer end thereof the box is cored or hollowed out to produce an oil-chamber 8, the entrance-opening 9 of which is formed by the rearwardly-curved forward edge 8', of the enlargement 4' and the front wall of the box, said opening being normally closed by a dust-proof lid or cover 10 of the 50 usual construction. By having the forward

edge of the central enlargement curved downwardly and rearwardly, as shown, it serves to deflect or properly direct the oil or other lubricating material into the oil-chamber. The oil-chamber 8 is, in accordance with my 6 invention, divided into a pair of compartments 11 12 by a vertical wall or partition 13, formed integral with the body-wall of the box and disposed beneath the journal 3, adjacent to the outer end thereof, the upper edge 6 of the partition being substantially in contact with the surface of the journal, thus rendering said compartments to all intents and purposes practically wholly separate and distinct.

In practice the compartment 11 is filled with 7 waste or other suitable absorbent packing material and the compartment 12 is charged with a supply of lubricant, with which latter the packing is also saturated. During rotation 7 the journal receives upon its outer end lubricant from the compartment 12 and feeds the same over the upper edge of the partition onto the packing within the compartment 11, and the packing in turn supplies the lubricant to the face of the journal. Thus the waste is 8 constantly supplied with and spreads the lubricant smoothly and evenly over the surface of the journal, while the latter, which as usual has a certain amount of endwise movement, is prevented from shifting or displacing the 8 packing, owing to the latter being positively retained in place by the partition 13.

It will be observed that owing to the upper 9 edge of the partition being arranged in close proximity to the face of the journal the oil from the supply-compartment 12 will be fed gradually to the packing in compartment 11, thereby maintaining the packing sufficiently saturated for properly lubricating the journal, but at the same time obviating a needless waste of the lubricant, owing to an undue flow of the latter to the packing. Further, by arranging the oil-receiving compartment at the front of the journal the supply of lubricant 9 therein may be more readily replenished, and by arranging the packing-receiving compartment at the rear of the journal the packing may be adapted for spreading lubricant upon the surface of and practically throughout the entire length of the journal.

From the foregoing it is apparent that I produce a simple inexpensive device which in practice will efficiently perform its functions. In attaining these ends it is to be understood that I do not limit myself to the precise de- 1

tails herein set forth, inasmuch as minor changes may be made therein without departing from the spirit of the invention.

Having thus described my invention, what I claim is—

A journal-box formed of a single casting provided with a central transversely-disposed enlargement having a curved bottom and defining oppositely-disposed laterally-projecting seating - flanges having bolt - receiving openings formed therein, the body of the casting beneath said enlargement being cored or hollowed out to form an oil-well the front wall of which is spaced from the front edge of the enlargement to form an oil-supply opening, there being an opening formed in the rear wall of the casting communicating with the oil-well for the reception of a journal, said opening being of greater diameter than that of the

journal to permit the insertion of a journal-brass between said journal and the curved bottom of the central enlargement, a vertical partition formed integral with the casting and provided with a terminal concavity arranged in horizontal alinement with the lower wall of the journal-receiving opening, said partition dividing the oil-well into a plurality of lubricating-compartments of unequal size, and a lid hinged to the central enlargement of the casting and adapted to normally cover the oil-supply opening.

In testimony that I claim the foregoing as my own I have hereto affixed my signature in the presence of two witnesses.

CHARLES JACOB GUSTAFSON.
